Primary Examiner—Louis S. Zarfas

Assistant Examiner—Monica A. Weingart

Attorney, Agent, or Firm—D. Peter Hochberg; Mark Kusner**[57] CLAIM**

The ornamental designs for a riser design for an archery bow for right or left hand, as shown and described.

DESCRIPTION

FIG. 1 is a reduced left side elevational view of a riser design for an archery bow for right or left hand showing my new design;

FIG. 2 is a left side elevational view thereof;

FIG. 3 is a rear elevational view thereof;

FIG. 4 is a right side elevational view thereof;

FIG. 5 is a front elevational view thereof; and,

FIG. 6 is a top plan view, the bottom being a mirror image thereof.

The broken line showing of limbs, a bow string, and a broken away partial arrow, in FIG. 1, an arrow rest and partial arrow, in FIG. 3, and an arrow rest, in FIG. 5, is for illustrative purposes only and forms no part of the claimed design.
